UNITED STATES PATENT OFFICE.

ROBERT T. CAMPBELL, OF KANSAS CITY, MISSOURI.

PACKING AND METHOD OF MAKING SAME.

1,210,273.

Specification of Letters Patent. Patented Dec. 26, 1916.

Application filed March 30, 1916. Serial No. 87,752.

To all whom it may concern:

Be it known that I, ROBERT T. CAMPBELL, a citizen of the United States, residing at Kansas City, in the county of Jackson and State of Missouri, have invented a certain new and useful Improvement in Packings and Methods of Making Same, of which the following is a specification.

My invention relates to packing and method of making the same.

It relates particularly to packing adapted for piston rods and the like.

One of the objects of my invention is to provide a packing, which is economical to manufacture and which will be efficient and durable.

A further object of my invention is to provide an improved method by means of which packing of the kind described may be cheaply manufactured.

Other novel features of my invention are hereinafter fully described and claimed.

In the accompanying drawing which illustrates my improved packing and the preferred method of making the same, Figure 1 is a vertical sectional view of a series of convolutions or rings of my improved packing shown mounted on a piston rod and in a packing box. Fig. 2 is a perspective view 30 of a bar of my improved packing. Fig. 3 is a perspective view of a bar prior to its being severed longitudinally to form two bars of packing.

Similar reference characters designate 35 similar parts in the different views.

A bar of my improved packing consists of a series of longitudinal laminations, preferably composed of the usual flexible fabric 1 and rubber 2 arranged alternately and 40 united together in the usual manner. The bar, shown in Fig. 2, has an inner flat side 3, which is adapted to bear against the periphery of a piston rod 4. The packing bar has two parallel sides 5, preferably disposed 45 at right angles to the inner side 3. The outer side 7 of the packing bar, which is adapted to bear against the inner side of a packing box 6, is of a form other than flat, and, as shown in the drawing, is preferably 50 convexly arcuate, the convex side being forced tightly against the inner wall of the box 6.

The laminations 1 and 2 are preferably disposed parallel with the sides 5, their longitudinal edges forming the inner side 3.

Embedded in the bar may be provided the

usual rubber core 8, disposed longitudinally and embraced by the laminations 1 and 2.

By having the inner side 3 of the bar flat, and the sides 5 parallel with each other and at right angles to the side 3, an efficient 60 wearing surface for bearing against the rod 4 is obtained, and leakage around the packing is avoided. By having the outer side 7 other than flat, and, preferably, convexly 65 arcuate, as shown, opportunity is afforded for the expansion of the packing within the box 6, when the piston rod 4 becomes heated and thereby expands the packing.

With packing which is circular in cross 70 section, opportunity for expansion is afforded, but an efficient wearing surface is not provided. With the packing rectangular in cross section, an efficient wearing surface is provided, but room for expansion is 75 not afforded, so that, with the last mentioned type of packing, when the piston rod becomes heated, undue wear of the packing occurs due to the incapability of the packing to expand in the space provided for it. 80 With my improved construction, a good wearing surface is provided, a tight packing afforded, and undue wear avoided by reason of the packing being permitted to expand, when heated, owing to the arcuate 85 form of the outer side.

In use, the improved packing may be employed as separate rings, as is usual, or it may be employed in the form of a helix, a manner of use also well known. 90

In the manufacture of the packing, the laminations are preferably formed into a bar which is approximately elliptical in cross-section, as shown in Fig. 3, the bar having two parallel sides connected by two 95 arcuate sides. The bar is then longitudinally severed at right angles to the two parallel sides, as denoted by the dotted line 9 in Fig. 3.

When the finished packing bar contains a 100 rubber core 8, the original bar of which the packing bar forms a half, is provided with two cores 8, as shown in Fig. 3, which are respectively disposed parallel with and respectively along opposite edges of a plurality of longitudinal layers which are disposed side by side. Around these longitudinal layers and the cores 8 is then wound a strip of material comprising flexible fabric between the adjacent layers of which are 105 layers of rubber. The bar thus formed has a cross section, such as is shown in Fig. 3,

two parallel sides being connected by two arcuate sides. This bar is then longitudinally severed between the cores 8 along the dotted line 9, thereby forming two complete packing bars, approximately semi-elliptical, having a flat inner side 3, two parallel sides 5 at right angles to the side 3 and an arcuate outer side 7, as shown in Fig. 2.

I do not limit my invention to the structure shown and described, as modifications, 10 within the scope of the appended claims, may be made without departing from the spirit of my invention.

What I claim is:

- 15 1. A packing having two sides at right angles to its inner side and having an outer side other than flat, the packing comprising laminations the longitudinal edges of which form said inner side.
- 20 2. A packing having two sides at right angles to its inner side and having an arcuate outer side, the packing comprising laminations the longitudinal edges of which form said inner side.
- 25 3. A packing having two sides at right angles to its inner side and having a convex outer side, the packing comprising laminations the longitudinal edges of which form said inner side.
- 30 4. A packing having a flat inner side and two sides at right angles to the inner side, and having an outer side other than flat, the packing comprising laminations the longitudinal edges of which form said inner side.
- 35 5. A packing having a flat inner side and two sides at right angles to the inner side, and having an arcuate outer side, the packing comprising laminations the edges of which form said inner side.
- 40 6. A packing having a flat inner side and

two sides at right angles to the inner side, and having a convex outer side, the packing comprising laminations the edges of which form said inner side.

7. The method of making packing 45 consisting in forming a bar of alternate longitudinal laminations of fabric and rubber, the bar in cross section having two sides disposed parallel with each other and connected by arcuate sides, and then longitudinally severing the bar through the parallel sides at right angles thereto.

8. The method of making packing 50 consisting in forming a bar comprising laminations of flexible material, the bar in cross-section forming a figure having parallel sides and arcuate ends, and then longitudinally severing the bar through the parallel sides at right angles thereto.

9. The method of making packing 55 consisting in forming a bar by winding upon each other layers of flexible material so as to form in cross section a figure having parallel sides and arcuate ends, and then longitudinally severing the bar through said parallel sides at right angles thereto.

10. The method of making packing 60 consisting in forming a bar by arranging a series of longitudinal layers of flexible material side by side, then disposing two parallel rubber cores respectively against the two sets of longitudinal edges of said layers, then winding around said cores and said layers, a series of layers of flexible material, and then longitudinally severing said bar 70 between said cores and parallel therewith.

In testimony whereof I have signed my name to this specification.

ROBERT T. CAMPBELL.
